SPRAYING APPARATUS

Harry M. Reynolds, Columbus, Ohio

Application November 5, 1941, Serial No. 417,928

3 Claims. (Cl. 91—45)

My invention relates to a spraying apparatus. It has to do, more particularly, with spraying apparatus which is particularly useful on a glass-forming machine for spraying a lubricant into the glass molds before the molten glass is supplied thereto. However, my invention is not necessarily limited thereto.

At the present time, it is customary in glass plants to use oil or similar liquid lubricants. It is important that the liquid lubricant be atomized and sprayed on the molds in order to uniformly coat the molds with a film of the lubricant. Considerable difficulty has been encountered in providing suitable spraying apparatus for insuring that the entire mold will be covered with the lubricant and this is particularly true when large molds are employed. It is necessary that such apparatus be capable of adjustment quickly and easily without interrupting the operation of the forming machine which in modern glass plants operates at a very high speed. Furthermore, it is necessary that such apparatus be of such a nature that it will not be detrimentally affected by the high temperatures encountered adjacent glass-forming machines.

One of the objects of my invention is to provide spraying apparatus which is particularly useful for spraying a lubricant on large glass molds in such a manner that the molds will be uniformly coated with the lubricant over the entire surface of the cavity thereof.

Another object of my invention is to provide spraying apparatus of the type indicated which may be adjusted quickly and easily without interrupting operation of the apparatus.

Another object of my invention is to provide apparatus of the type indicated which is of such a structure that it will readily withstand the high temperatures and the rugged use to which it is subjected when used in connection with a glass-forming machine.

In its preferred form my invention contemplates the provision of spraying apparatus comprising a rotatable carrier adapted to carry a plurality of spraying heads. These spraying heads may be of the type disclosed in my Patent No. 2,237,842 which issued April 8, 1941. The carrier is rotated by means of an air motor which is associated therewith. The air supply for such a motor is readily available when my apparatus is used in connection with a glass-forming machine. The carrier is adapted to be disposed over a glass mold and to rotate relative to the mold about the axis of the mold. This will insure that the lubricant will be sprayed

uniformly over the entire surface of the mold cavity. The spraying heads are so mounted on the carrier that the angle thereof may be readily adjusted to insure proper uniform coverage of the mold cavity. Furthermore, the spraying heads may be readily adjusted to vary the amount of lubricant sprayed therefrom. All of these adjustments may be easily and quickly made without operating any controls to interrupt rotation of the carrier. It is merely necessary to grasp the carrier and stop rotation thereof while the adjustments are being made.

The preferred embodiment of my invention is illustrated in the accompanying drawings wherein similar characters of reference designate corresponding parts and wherein:

Figure 1 is a view partly in side elevation and partly in vertical section of spraying apparatus constructed according to my invention, the sectional part being taken substantially along line 1—1 of Figure 2.

Figure 2 is a horizontal sectional view taken substantially along line 2—2 of Figure 1.

Figure 3 is a perspective view of my apparatus showing it associated with a glass mold.

Figure 4 is a diagrammatic view showing a valve control for the air motor.

With reference to the drawings, I have illustrated my spraying apparatus as consisting mainly of a rotatable carrier 1, carrying a plurality of spray heads 2, which is driven by means of an air motor indicated generally by the numeral 3. As shown in the drawings, particularly in Figures 1 and 3, the housing 4 of the motor has a boss 5 on its lower surface which is bolted to the outer end of a horizontal arm 6 by means of bolts 7. A similar boss 5a is provided on the top of the housing so that, if desired, the housing may be attached to the lower surface of an arm like the arm 6. The arm 6 may be clamped to a post 8 by clamping means 9. The entire unit is adapted to be disposed in such a position that the rotatable carrier 1 will be over a mold which may be one of a plurality of molds carried by the glass-forming machine.

The housing 4 of the motor 3 consists of a bottom portion 10, a block portion 11 and a top portion 12. Bolts 13 hold these various portions in proper association. As shown best in Figure 2, the block portion 11 has a pair of cylindrical cavities 14 formed therein. These cavities are disposed side by side, substantially tangential to each other, and are in communication with each other at their adjacent edges, as shown in Figure 2. Each of these chambers 14 has a gear 15

disposed therein. Each of the gears 15 consists of a central body portion 16 which closely fits with the lower surface of the top portion 12 and the upper surface of the bottom portion 10. Each gear has a plurality of radially extending circumferentially spaced teeth 17 which have flat outer ends 18 that lie closely adjacent the wall of the cavity 14. These two gears 15 mesh with each other, as indicated in Figure 2. A conduit 19 is connected to one side of the housing 4 and is directed tangentially relative to the meshing portions of the gears 15. Another conduit 20 is similarly disposed in the opposite wall of the housing 4. One of the gears 15 is carried by a short shaft 21 which is rotatably mounted in bushings 22 at the upper and lower ends thereof which are carried by the portions 10 and 12. The other gear 15 is carried by a hollow shaft 23 which is rotatably carried in bushings 24 and 24a disposed in suitable openings in the bottom portion 10 and top portion 12. The gears 15 are tightly fitted on and rotate with the shafts which carry them.

It will be apparent from Figure 2 that if air under pressure is allowed to enter through the conduit 19, it will act on the teeth 17 in the manner indicated by the arrows to rotate the left-hand gear 15 counterclockwise and the right-hand gear 15 clockwise. The exhaust air will escape through the conduit 20. Because of the tight fit between the top and bottom surfaces of the gears, the outer ends of the teeth 17 and the adjacent surfaces of the housing, very little air will escape between these adjacent surfaces and most of it will act to produce rotation of the gears. If the direction of the air is reversed, that is, if the air enters through conduit 20 and escapes through conduit 19, the direction of rotation of the gear 15 will be reversed.

For accomplishing this reversal, I may provide a valve control of the type indicated in Figure 4. The valve 25 comprises a cylindrical housing 26 which has an opening 19a, connected to line 19, and an adjacent exhaust opening 19b. It is also provided with an opening 20a, connected to line 20, and an adjacent outlet opening 20b. Within the housing 26 a valve core 27 is rotatably mounted. This member has grooves 19c and 20c formed at diametrically opposed points. It is also provided with a Y-shaped air passageway having branches 19d, 20d and 28. The outer end of branch 28 is connected to a groove 29. An opening 30 is provided for the main air supply. In Figure 4, the valve is shown in such position that air will enter housing 4 through line 20. Air will enter through inlet 30 into branch 28 and branches 19d and 20d of the air passageway. However, the end of the branch 19d is closed. The air entering branch 20d will flow through line 20 into housing 4. It will exhaust through line 19, groove 19c and outlet 19d. If the core 27 is rotated slightly clockwise, the branch 19d will communicate with opening 19a while the opening 20a will communicate with outlet 20b through groove 20c. Then, air will flow into line 19 and exhaust from line 20. In either position of the valve, the main inlet 30 is connected with branch 28. The valve may also be rotated to a neutral position. Thus, it will be apparent that by operation of the valve the air motor may be reversed or may be stopped completely.

It will be noted that the hollow shaft 23 projects a considerable distance below the housing 4. The carrier 1 is provided with a vertically

disposed solid shaft portion 31 which has a chuck portion 32 on its upper end adapted to receive the extension of the shaft 23. Clamping means 33 serves to clamp chuck portion 32 to the extension of the hollow shaft. The lower end of the shaft portion 31 is shown as being square for receiving the inner ends of four horizontally disposed spray head supporting arms 34 which are bolted thereto between upper and lower shoulders 35 and 36. Although I have shown four of these supporting arms, it is to be understood that any desired number may be provided. Each of the arms 34 is provided with a series of openings 37 in any of which a bolt may be disposed which is threaded to the upper end of a spray head 2. Thus, each spray head 2 may be disposed at any selected distance from the axis of rotation of shaft 31 and may be disposed at any angle relative to the arm 34. Thus, these heads may all be so disposed relative to each other that the entire surface of the mold cavity will be subjected to the spray. The heads 2 are preferably of the construction illustrated in my Patent No. 2,237,842.

Each of the spray heads has a cap 38 which may be adjusted to change the amount of liquid spray, as disclosed in said patent. Also, as disclosed in said patent, each of the spray heads has connected thereto an air line 39 and an oil line 40 which are in the form of flexible conduits. Each line 40 is connected to a valve cock 41 carried by a fitting 42 threaded into the upper portion of shaft 31 and communicating with a passage 43. Similarly, each of the air lines 39 is connected to a valve cock 44 carried by a fitting 45 threaded into the upper portion of shaft 31 and communicating with a transverse passage 46. The passage 46 is in communication with the bore 47 formed within hollow shaft 23. The passage 43 is in communication with the bore in a tube 48 which passes upwardly through the shaft 23.

The upper end of the bore 47 is closed by a solid portion 49 of shaft 23 through which the oil tube 48 passes. The upper end of bore 47 is provided with transversely extending inlet openings 50 which communicate with an annular chamber 51 formed between upper and lower portions of the bushing 24a. Space 51 communicates with a line 52 which is connected to a source of main air supply which is under the control of a valve cock 53.

The oil tube 48 extends upwardly through a packing gland indicated generally by the numeral 54. It is connected to a tube 55 which is connected to a suitable source of oil. Tube 55 is threaded into a packing gland supporting portion 56 which is supported on the top portion 12 of housing 4 by means of bolts 57 and spacers 58. The support 56 has a depending threaded boss 59 and has a chamber for receiving packing material 60 which is disposed around tube 48. A sleeve 61 is disposed within boss 59 and is adapted to compress the packing around tube 48. Sleeve 61 is adjustably held in position by means of a nut 62 threaded on portion 59 and locked in position by a nut 63. The lower end of tube 48 is connected to shaft 31 so that it will rotate therein. Thus, tube 48 will rotate relative to conduit 55. However, there will be no leakage of oil at this point because of the packing gland 54.

In the use of this apparatus, oil from the source of supply is allowed to enter through conduit 55. This oil will flow down through tube

48 and out through fittings 42, past valve 41 which will be opened, and into lines 40. Valve cock 53 will be open, allowing air to flow through conduit 52, through bore 47, through bore 46, through fittings 45, past valves 44 which will be opened, into lines 39. Thus, the spray heads 2 will be operated in the manner disclosed in my patent. The valve 25 will be actuated to rotate the carrier 1 in the proper direction. The direction of rotation may be reversed at any time desired. During rotation of the carrier 1, if it is desired to adjust the angle of any of the spray heads 2 or the cap 38 of any of the spray heads, it is not necessary to actuate the valve 25 to stop rotation of the carrier. It is merely necessary to grab one of the arms 34 and hold the carrier with sufficient force to overcome the air pressure against the teeth of gears 15. This will prevent rotation of the carrier and, consequently, rotation of gears 15 during the adjustment. The speed of rotation of gears 15 may be controlled by adjusting valve cock 190 or 200 which are connected to conduits 19 and 20, respectively, at the housing 4. This will vary the amount of air entering into the housing.

It will be apparent from the above description that I have provided a spraying apparatus embodying a rotatable carrier which will rotate the spraying unit relative to a mold to insure that all surfaces of the cavity thereof will be uniformly coated with the lubricant. The speed of rotation of the carrier may be controlled readily and also the direction of rotation thereof may be quickly changed. Due to the fact that the carrier is driven by an air motor, the carrier may be stopped without operating any control in order to adjust the spray heads. This is important since frequent adjustment of the spray heads are necessary and it is not necessary, therefore, to interrupt operation of my spraying apparatus. My spraying apparatus is of such a nature that it is of a very rugged construction and will withstand the high temperatures to which it might be subjected.

Various other advantages will be apparent from the preceding description, the drawings and the following claims.

Having thus described my invention, what I claim is:

1. Spraying apparatus of the type described comprising an air motor, said air motor comprising a housing having intermeshing gears disposed therein, means for supplying air into said housing to cause rotation of said gears, one of said gears being supported by a shaft extending from the housing, a spray head supported by said shaft, and means for supplying liquid and air to said spray head.

2. Spraying apparatus of the type described comprising an air motor, said air motor comprising a housing having a pair of substantially tangentially disposed cavities formed therein, each of said cavities having a gear disposed therein, said gears meshing with each other, each of said gears being carried by a shaft rotatably mounted in said housing, means for supplying air between said intermeshing gears to cause rotation thereof, one of said shafts extending from said housing, and a spray head supported by said shaft.

3. Spraying apparatus of the type described comprising an air motor, said air motor comprising a housing having a pair of substantially tan-

gentially disposed cylindrical cavities formed therein in communication with each other, each of said cavities having a gear disposed therein, said gears meshing with each other, each of said gears being carried by a shaft rotatably mounted in said housing, means for supplying air into said housing between said intermeshing gears to cause rotation thereof, one of said shafts extending from said housing and being hollow, a spray head supported on said shaft, means for supplying air to the interior of said shaft, a liquid supply tube disposed within said shaft, and means for connecting said tube and the interior of said shaft to said spray head.

15 4. Apparatus according to claim 3 wherein means for supplying air into said housing comprises oppositely disposed conduits connected to said housing at opposite sides of the intermeshing gears and a valve for selectively controlling the supply of air and exhaust of air through said conduits.

20 5. Apparatus according to claim 3 wherein a plurality of spray heads are carried by said carrier and wherein a pair of conduits is connected to each of said spray heads and to said hollow shaft and liquid supply tube, said conduits having valve cocks disposed therein.

30 6. Spraying apparatus of the type described comprising an air motor, said air motor comprising a housing having a pair of substantially tangentially disposed cylindrical cavities formed therein in communication with each other, each of said cavities having a gear disposed therein, said gears meshing with each other, each of said gears being carried by a shaft rotatably mounted in said housing, means for supplying air into said housing between said intermeshing gears to cause rotation thereof, one of said shafts extending through said gear in both directions and projecting from said housing, said shaft being hollow, a spray head supported by the projecting portion of said shaft, means for supplying air to the interior of said shaft during rotation thereof, a liquid supply tube disposed within said shaft and adapted to rotate therewith, means for connecting said tube and the interior of said shaft to said spray head, said liquid supply tube projecting from said housing in a direction opposite to that of the projecting portion of said shaft, and means for connecting said tube to a stationary oil supply conduit, said means comprising a packing gland carried by said housing.

45 7. Apparatus according to claim 6 wherein the means for supplying air to said housing comprises oppositely disposed conduits connected to the housing and disposed substantially tangential relative to said gears, and a valve connected to said conduits and adapted to be selectively actuated to permit air to enter through one of said conduits and exhaust through the other or vice versa.

50 8. Apparatus according to claim 6 wherein the means for supplying air to said housing comprises oppositely disposed conduits connected to the housing and disposed substantially tangential relative to said gears, a valve connected to said conduits and adapted to be selectively actuated to permit air to enter through one of said conduits and exhaust through the other or vice versa, and a valve interposed in each of said conduits for controlling the amount of air entering into said housing.

HARRY M. REYNOLDS.
